UNITED STATES PATENT OFFICE.

DANIEL LOWENHAUPT AND CHARLES D. ROWE, OF MOUNT VERNON, INDIANA.

KNOCKDOWN SHIPPING BOX OR CRATE.

1,379,196.

Specification of Letters Patent.

Patented May 24, 1921.

Application filed August 10, 1920. Serial No. 402,531.

To all whom it may concern:

Be it known that we, DANIEL LOWENHAUPT and CHARLES D. ROWE, citizens of the United States, both residing at the city of 5 Mount Vernon, in the county of Posey and State of Indiana, have invented certain new and useful Improvements in Knockdown Shipping Boxes or Crates, of which the following is a specification.

10 This invention relates to knock-down shipping boxes or crates and has for its objects, first, the provision of an improved side and end construction possessing durability and strength, with adaptability for 15 quick and easy removal or replacement of either end and complete security when closed and sealed; second, an improved tongue and groove corner piece construction enabling the sides to be assembled or disconnected by 20 a sliding action without requiring the use of nails or other fastenings when the ends are in position; third, an improved side and end construction comprising box board and reinforcing corner pieces of wood, combined 25 with braces for the box board sides and ends whereby the box boards are strengthened and the construction is rendered relatively light; fourth, an improved construction whereby the ends are connected to the sides 30 by the braces and bolts or pins provided with seals so that the consignee may know that the box or crate has not been opened.

Our invention is susceptible of modification without departing from its essential 35 principles and the disclosure in the drawings and by way of the following description is to be considered as illustrative, instead of restrictive, of the scope of the invention.

40 In the accompanying drawings:

Figure 1 is a perspective view of the complete box or crate in sealed condition;

Fig. 2 is an end elevation, the end of the box being removed;

45 Fig. 3 is an elevation looking toward the inner face of the end which has been removed;

Fig. 4 is a longitudinal section through Fig. 1;

50 Fig. 5 is a detail perspective of one of the corner pieces, and

Fig. 6 is a similar view of one of the braces.

The box or crate comprises unitary sides 55 1 and unitary ends 2. One of the unitary

ends appears in Fig. 3 looking toward the inner face thereof.

Each side 1 comprises a strip or panel of box board 3, corner pieces 4, and brace 5 extending longitudinally of the box board 60 panel 3 and fastened thereto by internal staples or other fastening means 6. The ends 5^a of the braces 5 project beyond the ends of the box board panel 3 and are adapted to enter the openings or slots 7 in 65 the frame members 8 of the ends 2. Bolts 9 pass through openings 10 in the frame members 8 and through openings 11 in the ends 5^a, thereby securing the end sections 2 to the side sections 1. Seals 12 are employed for locking the bolts 9 so that the consignee may be assured that the box or 70 crate has not been opened. It is within the spirit of our invention to provide cross keys or cotters in lieu of the seals 12.

75 One of the corner pieces 4 is provided with a dovetailed channel 13 to receive a dovetail 14 on the other corner piece or rail 4. For instance, one of the box boards 3 will 80 carry at its opposite edges corner pieces 4 which have channels 13; and a box board 3 arranged at right angles thereto forming another side of the crate, will have dovetails 14 adapted to be received in the channels 13. Thus, each side 1 is a complete and 85 self-contained unit which is slidably connected to two of the remaining sides and, by the mere act of sliding the sides in relation to each other, they may be connected or disconnected.

90 The end sections 2 comprise the frame pieces 8 which are connected by a mortise and tenon joint 15, a panel of box board 16, and a brace 17 which has its ends seated in recesses in two of the frame pieces 8. 95 The slots 7 are provided in each of the frame pieces 8 and receive the ends 5^a as hereinbefore described.

100 The complete box or crate appears as in Figs. 1 and 4. The box board panels 3 and 16 constitute a sealed container for whatever goods is to be shipped. The braces 5 and 17 prevent any breaking out of the box board panels. The corner pieces 4 provide 105 strong corners for the box body. The ends 2 prevent any crushing of the crate as they are solid frames. We do not limit to the use of box board for the panels 3 and 16 nor to the use of wood for the braces 5 and 17 nor to the use of wood for the frame pieces 110

8. The purpose is to form the panels of relatively thin and light material and to reinforce them by rigid frames and corner pieces. Each side is unitary and each end 5 is unitary, so that the sides may be disconnected by sliding the corner pieces 4 of one side in relation to those of another side until they are completely detached, but this 10 sliding action is prevented when the ends 2 are in position. When the sides and ends are disconnected they may be stacked on each other for reshipment of the crate in knock-down condition. To obtain access to the interior of the crate, it is only necessary 15 to remove one of the ends 2.
- The box can then remain on end, in upright position and serve as a container for as long as desired.
- What we claim is:
- 20 1. A knock-down box or crate comprising sides each having a corner strip and a brace,

the corner strips having slidably detachable connecting means whereby one side is connected to another side, the braces having projecting ends, and ends for the box or 25 crate which have openings detachably receiving the projecting ends of the braces.

2. A knock-down box or crate comprising sides each having a corner strip and a brace, the corner strips having slidably detachable 30 connecting means whereby one side is connected to another side, the braces having projecting ends, ends for the box or crate which have openings detachably receiving the projecting ends of the braces, detachable 35 bolts passing through the projecting ends of the braces, and means for securing the bolts against detachment.

In testimony whereof we affix our signatures.

DANIEL LOWENHAUPT.
CHARLES D. ROWE.
